(57) **CLAIM**

The ornamental design for a semi-acoustic electric guitar as shown and described.

DESCRIPTION

FIG. 1 is top-front-left perspective view of a semi-acoustic electric guitar in accordance with the present design; FIG. 2 is a left-side view of the semi-acoustic electric guitar of FIG. 1;

FIG. 3 is a right-side view of the semi-acoustic electric guitar of FIG. 1; FIG. 4 is a top view of the semi-acoustic electric guitar of FIG. 1;

FIG. 5 is a bottom view of the semi-acoustic electric guitar of FIG. 1;

FIG. 6 is a front view of the semi-acoustic electric guitar of FIG. 1; and,

FIG. 7 is a rear view of the semi-acoustic electric guitar of FIG. 1.

The broken lines represent the portions of the semi-acoustic electric guitar that form no part of the claimed design.

1 Claim, 4 Drawing Sheets
